UNITED STATES PATENT OFFICE.

FRANK H. GATHERCOAL, OF WILMETTE, ILLINOIS.

DISAPPEARING SASH FOR PORCH CONSTRUCTIONS.

1,263,756.

Specification of Letters Patent. Patented Apr. 23, 1918.

Application filed March 19, 1917. Serial No. 155,846.

To all whom it may concern:

Be it known that I, FRANK H. GATHERCOAL, a citizen of the United States, residing at Wilmette, in the county of Cook and State of Illinois, have invented new and useful Improvements in Disappearing Sashes for Porch Constructions, of which the following is a full, clear, concise, and exact description, reference being had to the accompanying drawing, forming a part of this specification.

My invention has for its object the production of a device in which a perfect closure against the elements is provided.

15 A further object is the production of a device in which the sash may be rigidly locked in closed position.

A further object is the production of a simple and efficient device that can be easily 20 attached to constructions and one not liable to get out of order.

These and such other objects as may hereinafter appear are attained by my device, an embodiment of which is illustrated in the 25 accompanying drawing, in which—

Figure 1 represents a sectional view of a porch construction showing my device in position.

Fig. 2 represents a perspective view of the 30 spring locking member.

Like numerals of reference indicate like parts in the several figures of the drawing.

Referring now to the drawing which shows a porch sash equipped with my device 35 in closed position, A represents the outside casing, B the jamb, C the parting stop, D the stop, F the lower bar and G the upper bar of the sash, H the outside sill, I the inside sill, J the glass of the window, K the 40 pocket within which the window can be dropped, and L the corresponding pocket in the upper portion within which the window can be raised in order to permit the movement of my improved closure M. An ordinary mortise lift G', is set in the inner face 45 of the lower bar F.

The closure M is provided with a hinge N hingingly mounted on the inner sill I at O. The closure is provided with a downwardly 50 extending lip or bead P and an upwardly extending lip or bead Q. The hinge N, in addition to the leaves R—S which are screwed to the sill and side of the member M, has a supplemental tightening lever T 55 with an extended arm or handle U and an

upwardly extending gripping arm V terminating in a curved catch W. As shown in Fig. 1 the sash is closed and the catch W enters the mortise lift G' and its end engages a groove g in the mortise in the lower 60 bar. When the window is open the members V and U occupy the position shown in Fig. 2. The two members are then turned upwardly on the pivot S¹ until the catch W engages the mortise lift in the lower bar and the 65 lever U is swung down swinging the member T back into the position shown in Fig. 1 and locking the sash tightly against the closure M.

In order to release the sash, it is simply 70 necessary to swing the member U upwardly again and then the catch W is released and the parts swung back toward the inner sill I. The closure M may then be swung upwardly on the pivot O and the window sash 75 dropped into the pocket K after which the closure will be swung back entirely covering the pocket K and fitting closely over a raised lip or bead Z on the outside sill.

By this construction it is possible for me 80 to have the porch tightly inclosed by reason of the lip P engaging the bead Z and the lip Q engaging a corresponding cut 85 away portion in the inner surface of the lower sash F, making it impossible for any water or snow or wind to force its way between the sash and the sill.

While I have shown a method of closing this completely by my improved spring member, it is evident that other means may 90 be employed without departing from the spirit of my invention.

Having thus described my invention, what I claim as new and desire to secure by Letters Patent is:

1. The combination with a sash of a pocket positioned below said sash and adapted to receive the same, an inner sill, a covering member hingedly mounted on said inner sill and adapted to cover said pocket, a locking member mounted on the inside of said covering member and adapted to be brought into engagement with the sash to force the same down tightly against said covering member. 95 100

2. The combination with a sash of a pocket positioned below said sash and adapted to receive the same, a beaded front sill, an inner sill, a covering member hingedly mounted on said inner sill provided 110

with a downwardly projecting flange on its lower outer end and an upwardly projecting flange on its upper inner end, and adapted to cover said pocket, a locking member 5 mounted on the inside of said covering member and adapted to be brought into engagement with the sash to force the same down

tightly against said member and cause the lower flange on said member to engage the bead on the sill and the sash to engage the 10 upper flange.

In witness whereof I have hereunto subscribed my name.

FRANK H. GATHERCOAL.
